UNITED STATES PATENT OFFICE.

JOHN R. BARKER, OF CHICAGO, ILLINOIS.

IMPROVEMENT IN HOT-AIR FURNACES.

Specification forming part of Letters Patent No. 127,140, dated May 28, 1872.

SPECIFICATION.

To all whom it may concern:

Be it known that I, JOHN R. BARKER, of Chicago, in the county of Cook and State of Illinois, have invented certain Improvements in Heating-Furnace, of which the following is a specification, reference being had to the accompanying drawing.

My invention relates to hot-air furnaces; and consists in the novel construction and arrangement of the air and smoke flues in connection with the fire-pot and vapor-pan.

In the drawing, Figure 1 is a cross-vertical section on the line y y of Fig. 3. Fig. 2 is a cross-vertical section on the line z z of Fig. 4. Fig. 3 is a cross-horizontal section on the line v v of Fig. 1; and Fig. 4 is a cross-horizontal section on the line x x of Fig. 2.

In constructing my furnace I make a base, E, with an open bottom, and from the periphery of which a shell of mason work, A, or other suitable material is built, so as to inclose and leave an air-space, B, between it and the body of the furnace, as is clearly shown in all the figures. Upon the base is placed an ash-pit, F, with its opening arranged as shown, and over the ash-pit a fire-pot, G. This fire-pot is provided on its exterior with a series of radially-projecting flanges or ribs, a , having an offset or shoulder, b , near their lower ends, as shown clearly in Figs. 1 and 2. Around the lower ends of the flanges a and just below the shoulders b , is placed an annular vapor-pan, c , as shown in the same figures. Above the vapor-pan c , and resting upon the shoulders b of the fire-pot, is an annular drum, H, from the upper side of which are a series of flues, d , connecting it with the open space in the head of a cylinder, I, above the fire-pot. These flues d are return-flues to carry the smoke and draught from the fire-pot down to the drum, from which they pass out into the smoke-pipe J, as clearly shown in Fig. 1. The body of the cylinder I is sufficiently smaller in diameter than its head to be placed within the circle of the return-flues d , and is of the proper length to extend a little below the upper end of the fire-pot, and in diameter is larger than the fire-pot. Its lower end is provided with a ring,

f , the inner side of which fits close about the upper end of the pot. Within the cylinder I are arranged a series of air-flues, e , the lower ends of which open into the spaces above the flanges a , and their upper ends into the air-space above the body of the furnace, between it and its outer shell. From the upper end of the cylinder I is a pipe, K, connecting it with the smoke-pipe J, and in which is placed a damper, g , in order that the draught may be direct when desired, instead of through the return-flues. For the removal of the dirt, dust, &c., from the drum H, an opening, M, is provided, with a movable plate, h , and for cleaning the smoke-pipe and obtaining access to the damper, a removable section, N, is provided, all as shown in Figs. 1 and 2. The ordinary dumping-grate may be used, and the usual access for introducing the fuel provided.

The operation of this furnace will be readily seen. When the fire is kindled, and the water introduced into the vapor-pan by any suitable device, the smoke and draught will pass to the upper end of the cylinder I, then down into the drum H, and then on out through the smoke-pipe, heating thoroughly in the mean time the fire-pot and its flanges or ribs, the cylinder, smoke-flues, and drum, all of which radiate heat into the space between the body of the furnace and its shell. At the same time a current of cold air is coming in through the base of the furnace, and passing up between the flanges or ribs a and the drum H, and on up through the air-flues e , and out through their upper ends, becoming in its passage thoroughly heated. While this is going on the water in the pan c is being evaporated, and the vapor is mingling with the cold air as it passes up between the flanges or ribs on the fire-pot and the drum H. The air thus heated and moistened is then carried off into the building in the usual manner.

A furnace thus constructed furnishes an unusually large amount of heating and radiating surfaces. The flanges upon the fire-pot as well as the pot itself are, of course, heated the most, and it will be noticed they are so arranged that the cold air comes immediately in contact with them on entering the furnace, and

is kept in close contact with surfaces that are directly heated by the fire until it escapes out of the upper end of the body of the furnace. The vapor-pan, too, it will be seen, is so constructed as to afford a large evaporating surface, and is so arranged that the vapor is introduced into the air uniformly as it enters the furnace.

Having thus described my invention, what I claim is—

A hot-air furnace, consisting of the ribbed fire-pot G, drum H, ring f, flues d and e, and annular vapor-pan e, when constructed and arranged to operate substantially as herein described.

JOHN R. BARKER.
